UNITED STATES PATENT OFFICE.

FRED J. PARKER, OF MOOSE JAW, SASKATCHEWAN, CANADA, ASSIGNOR OF TWO-FIFTHS TO THOMAS FERGUSON ACHESON, OF YORKTON, SASKATCHEWAN, CANADA.

COVER REMOVER.

Application filed March 16, 1922. Serial No. 544,340.

To all whom it may concern:

Be it known that I, FRED J. PARKER, a citizen of the Dominion of Canada, residing at Moose Jaw, in the county of Moose Jaw and Province of Saskatchewan, Canada, have invented certain new and useful Improvements in Cover Removers, of which the following is a specification.

The present invention comprehends the provision of a device for removing covers from and attaching the same to sealers and the like.

The object of my invention is to provide a device of the character described constituting dual hingedly connected sections having side walls lined with a suitable composition adapted for gripping a sealer cover. The device is adapted to be positioned about the cover of a sealer and when pressure is exerted on the same, the device will grip the said cover firmly to facilitate the removing or tightening operation.

The nature and advantages of my invention will be more readily understood after a perusal of the following description, the descriptive matter being supplemented by the accompanying schematic illustrations, wherein:

Figure 1 is an interior perspective view of the device constructed in accordance with my present invention.

Fig. 2 is an exterior perspective view thereof.

Fig. 3 is a transverse vertical section as it would appear when taken on line 3-3 of Fig. 2 and

Fig. 4 is a similar view showing the device in closed position.

Referring to the drawings in detail, wherein like numerals of reference designate corresponding parts, the numerals 5 and 6 designate semi-circular plates which are hingedly connected as at 7, the spring 8 forming the hinge pin and the terminals 9

and 10 are connected to the semi-circular plates 5 and 6, which terminals serve as a tensioning means to keep the said plates in the position shown. The numerals 11 and 12 indicate walls substantial with the plates 5 and 6 and have ridges 13, 14, 15 and 16 disposed on the extremities thereof. The interior of the walls 11 and 12 are lined with a suitable composition.

In operation, when it is desired to remove a cover from or tighten the same on a sealer, the device is positioned over the sealer and the sections thereof tension together until the composition lining as described grips the surface of the cover. The ridges 13, 14, 15 and 16 provide means whereby the hands of the operator may rigidly grip the device, thus obviating slipping. It is apparent that with the use of this device, covers may be attached to or removed from sealers more expediently and with less difficulty.

Since probably the best results may be obtained from the invention as defined by the disclosure, the same may be well followed, but within the scope of the invention as defined by the appended claim, numerous minor changes may well be made.

What I claim as new is:

The improved cover remover described, comprising two semi-circular plates, and a spring forming a hinge pin hingedly connecting said plates with its terminals oppositely extended so as to engage said plates and thereby serving as tensioning means, said plates being formed with vertical walls having ridges to provide gripping means adjacent the abutting edges of said walls.

In testimony whereof, I affix my signature in the presence of two witnesses.

FRED J. PARKER.

Witnesses:

MAE FISHER,
BERTHA PARKER.
